UNITED STATES PATENT OFFICE.

JOHN GEORGE AULSEBROOK KITCHEN, OF MANCHESTER, ENGLAND,
ASSIGNOR TO THE MANCHESTER CYCLE COMPONENTS, LIMITED,
OF SAME PLACE.

LAMP.

SPECIFICATION forming part of Letters Patent No. 593,396, dated November 9, 1897.

Application filed April 8, 1897. Serial No. 631,220. (No model.)

To all whom it may concern:

Be it known that I, JOHN GEORGE AULSEBROOK KITCHEN, a subject of the Queen of Great Britain, and a resident of Manchester, 5 in the county of Lancaster, England, have invented new and useful Improvements in Lamps, of which the following is a specification.

This invention relates to lamps for cycles and other vehicles; and it consists in an improved construction of lamp, the improvements having for their object the production of a steadily-burning lamp not affected by the wind and throwing a good light upon the ground in front of the cycle or vehicle and to render the quantity of oil contained in the lamp visible.

In order that my invention may be more readily understood, I have attached hereunto 20 a sheet of drawings, to which I will now refer.

In the said drawings, Figure 1 represents a front elevation of my improved lamp; Fig. 2, a side sectional elevation; and Fig. 3, a plan in section, looking upon the top of the oil-reservoir of the same.

In the several views like parts are indicated by like letters of reference.

I form the case *a* of the lamp in a hemispherical or preferably a hemiellipsoidal or 30 similar dished or cupped form, with a door *b* containing a glass plate *b'* in front of the case. I form an oil-reservoir *c* so as to conform in shape to the lower half of the case. The case may form one side of said reservoir, the front 35 side *c'* of the reservoir being of a similar shape, but preferably so formed that the sides are farthest apart in the center of the case and approach each other toward the circumference. A separate reservoir of this shape 40 may in some cases be formed to fit into the case.

The drawings illustrate a miniature lamp having a comparatively large reservoir, which is obtained by extending the reservoir *c* backward in the center part, as illustrated by the projection *c'*. At the top the reservoir is provided with a filling-tube *c'*, protruding from the case and closed by a cap *c*. At about the middle of the bottom of the cavity formed 45 by the front side of the reservoir I attach

thereto a vertical tube *d* with a slot *d'* in front, and fit tightly into the same a glass tube *d*, closing the top by a cap *d*, containing a wick-tube *d* with adjusting-pinion, the stem *d* of which passes to the outside of the lamp and terminates with a milled disk *d*. Through the glass the quantity of oil in the reservoir can be seen, and the glass or metal tube is in some cases marked at different levels to indicate the length of time for which the oil-supply suffices, in the manner shown by the lines *d*. In front of the reservoir I arrange a metal reflector *e*, fitting to the front side of the reservoir and being of a symmetrical shape in the upper half, so that a hollow 60 space of similar shape as that the reservoir occupies is left between the reflector and the case in the upper half. The reflector is made removable to facilitate cleaning. It contains an opening *e'* in the top above the burner, 70 protected by a shield *e*, for the escape of the smoke, and the case has an opening *e* or may have a number of openings in the top for the same purpose. Round the edge the reflector has a series of air-inlet holes *e*, and the case 75 is formed with similar holes *e*. Any wind blowing in through the openings becomes distributed in the space between the reflector and case and cannot extinguish the lamp.

Side doors for lighting the lamp may be 80 formed in the well-known way at one side or both sides of the case, closed with glass doors to show side lights, and openings formed in the reflector opposite each door for passing the match through. These side doors, however, may be omitted.

The lamp-case is formed with the usual spring device *f* for attaching it to the lamp-bracket.

I claim—

1. In a lamp the combination of a concave reflector distant from the back of the lamp-case, an oil-reservoir between the lower part of the said reflector and case, a slotted metal tube in front of the reflector in open communication with said reservoir and carrying a wick-tube and adjusting device, and a glass fixed liquid-tight in said metal tube. 95

2. In a lamp the combination of a concave reflector, an oil-reservoir composed of a re- 100

ceptacle extending behind the lower part of the reflector and a glass tube in front of the same, incased in a slotted metal tube, a cap with wick-tube and adjusting device on the 5 top of said tube, a pipe rising from the top of the oil-reservoir through the case and closed by a cap, air-holes round the lower edge of the case and reflector, outlet-holes in the top of the reflector and case with a shield

between them, and a spring-carrier attached 10 to the back of the lamp.

In testimony whereof I have hereunto set my signature in the presence of two witnesses.

JOHN GEORGE AULSEBROOK KITCHEN.
